UNITED STATES PATENT OFFICE.

GASPAR HUNZIKER, OF CLOVERDALE, CALIFORNIA.

DESIGN FOR A WIRE FENCE.

SPECIFICATION forming part of Design No. 14,442, dated November 27, 1863.

Application filed September 17, 1863. Term of patent 14 years.

To all whom it may concern:

Be it known that I, GASPAR HUNZIKER, a citizen of the United States, residing at Cloverdale, in the county of Sonoma and State of California, have invented and produced a new and original Design for Wire Fences, of which the following is a specification, reference being had to the accompanying drawing, forming part thereof.

10 My design relates to wire fences; and it consists in the combination of two or more nettings with different-sized meshes, as will be more fully explained by reference to the accompanying drawing, which represents an elevation showing a section of fence embodying my design.

15 The leading feature of my design consists of a series of parallel horizontal sections of netting, having meshes of different sizes, said sections being united at their edges so as to

A A are the terminal posts or bars of the sections, which are separated so as to make the sections of any desired length. The first section, B, has a mesh of any desired fineness. 25 The second section, C, has a mesh considerably coarser, and the third section, D, is a still coarser mesh, the whole thus forming a complete and continuous panel.

Having thus described my design, what I claim is—

20 The design for fence-panels, consisting of parallel horizontal sections of netting having meshes of different fineness, substantially as herein described and shown. 35

In witness whereof I have hereunto set my hand.

GASPAR HUNZIKER.
